[57] CLAIM

The ornamental design for a handled clamp for ground glass ball and socket joints or the like, as shown and described.

DESCRIPTION

FIG. 1 is a bottom, side perspective view of a handled clamp for ground glass ball and socket joints or the like, showing my new design;

FIG. 2 is a front elevational view thereof, the rear being identical;

FIG. 3 is a side elevational view thereof, both sides being identical;

FIG. 4 is a top, side perspective view thereof, the portion of the ball and socket joint being shown in broken lines for illustrative purposes only;

FIG. 5 is a top plan view thereof;

FIG. 6 is a bottom plan view thereof.

FIG. 1.

FIG. 2.

FIG. 3.

FIG. 4.

FIG. 5.

FIG. 6.
